UNITED STATES PATENT OFFICE.

WILLIAM F. PAGE, OF YOUNGSTOWN, OHIO.

DRIER.

1,217,051.

Specification of Letters Patent. Patented Feb. 20, 1917.

Application filed November 24, 1914. Serial No. 873,773.

To all whom it may concern:

Be it known that I, WILLIAM F. PAGE, a citizen of the United States, residing at Youngstown, in the county of Mahoning and 5 State of Ohio, have invented certain new and useful Improvements in Driers; and I do hereby declare the following to be a full, clear, and exact description of the invention, such as will enable others skilled in the art 10 to which it appertains to make and use the same.

This invention relates to excrement driers, and the primary object of the invention is to provide a drier which utilizes heated gases 15 for removing the liquid products from human excrement and leaving the nitrate proclivities of the excrement for forming a commercial fertilizer.

Another object of this invention is to provide a drier as specified which embodies a casing having a plurality of staggeredly disposed pans positioned therein for retaining the excrement, which pans are spaced vertically from each other so as to permit of 20 the passage of heated gases over the pans for removing the liquid from the excrement and also to provide bypasses for carrying off the vaporized liquids or by-products of the drying of the excrement, and depositing 25 them in a suitable by-product retaining receptacle, which will be subjugated to heated gases for decomposition or vaporization and will pass off with the gases.

With the foregoing and other objects in 30 view this invention consists in such novel features of construction, combination and arrangement of parts as will be hereinafter more fully described, illustrated in the accompanying drawings and claimed.

40 In describing the invention in detail, reference will be had to the accompanying drawings wherein like characters designate like or corresponding parts throughout the several views, and in which:—

45 Figure 1 is a vertical sectional view through the nitriary,

Fig. 2 is a fragmentary side elevation of the nitriary, and

50 Fig. 3 is a fragmentary cross sectional view through the nitriary taken at right angles to the section illustrated in Fig. 1.

Referring more particularly to the drawings, 1 designates the housing or outer casing of the nitriary or excrement drier, which 55 is substantially rectangular shaped and has its lower end or bottom open and adapted

for seating upon a fire box indicated at 2 in Fig. 2 of the drawings. The fire box 2 may be constructed in any suitable manner. The housing 1 is mounted upon the fire box 60 2, so as to serve as a flue or stack for carrying off the products of combustion of and heated gases from a fire built within the fire box, the purpose of which will be hereinafter more fully described. 65

The housing 1 has a removable cover 3 mounted upon the upper end thereof, which has a flue or stack 4 formed on the center of the upper side thereof to complete a draft through the housing and fire box. 70

The housing 1 has a plurality of platforms 5 secured to the sides thereof and disposed in staggered relation to each other, so as to cause the heated gases rising from the fire box 2 to travel in a tortuous path upwardly 75 through the housing, and travel horizontally above each and every platform 5, to the end thereof, from whence they travel vertically until they strike the bottom of the platform above which will deflect the products of 80 combustion and cause them to travel horizontally across the pans directly beneath the platform which the products strike.

The platforms 5 are braced intermediate 85 their ends by bracing bars 6 which are secured to the sides of the housing 1 and extend transversely therethrough, engaging the under surface of the bottom of the platforms.

The platforms 5 have their marginal side 90 edges bent upwardly and horizontally, as is clearly shown at 7 and 8 in Fig. 1 of the drawings, so as to form receiving guideways for pans 9. The pans 9 are detachably or slidably mounted upon the platforms 95 5, and they are provided for retaining the excrement to be acted upon by the products of combustion passing upwardly through the housing.

The housing 1 is provided with openings 100 10 formed in the sides thereof, and in alignment with the platforms 5, so as to permit of the mounting of the pans 9 upon the platforms. The openings 10 are normally closed by doors 11, which are hingedly connected to the housing, as is shown at 12, and which have suitable catch mechanisms 13 secured to their free ends, for securely holding them in closed position. 105

Pipes 15 and 16 are disposed upon opposite sides of the housing 1, and extend vertically along the sides, being spaced there- 110

from. The pipe 15 has its upper and lower ends bent angularly to the vertical section thereof, forming elbows 17 and 18. The elbow 17 is inserted through one side of the 5 housing 1 and has its open end positioned a short distance above the upper surface of the pans 9 which is mounted upon the lowermost of the platforms 5. The upper elbow 18 of the pipe 15 extends through the 10 side of the housing 1 and is positioned a short distance above the upper edge of a receptacle 19, which is mounted in the upper end of the housing 1 above the uppermost platforms 5 and a short distance inwardly 15 below the inner terminal of the flue 4, as is clearly shown in Fig. 1 of the drawings. The receptacle 19 has its edges spaced from the inner surface of the sides of the housing 1, so as to permit the heated gases from 20 the furnace or fire box 2 to pass about all sides of the receptacle for evaporating the by-products and causing them to pass out of the casing with the products of combustion.

25 The pipe 15 has joints 20 formed thereon intermediate of the elbow or angled ends 17 and 18, which joints extend through the sides of the housing 1 and are positioned above certain of the platforms 5, which are 30 secured to the sides 21 of the housing 1 along side of which the pipe 15 is mounted.

35 The pipe 16 which is positioned along side the side 22 of the housing 1, or in other words, the side directly opposite to the side 21, has its ends bent angularly for forming elbows 23 and 24. The elbow 23 extends through the side 22 and is positioned above the upper surface of the receptacle 19, similar to the positioning of the elbow 18 of the 40 pipe 15. The lower elbow 24 extends through the side 22 and is positioned above the upper surface of the platform 5 which is next to the lowermost platform positioned within the housing. The pipe 16 has joints 25 45 formed thereupon, which extends through the side 22 of the housing and are positioned above the alternate platforms 5 which are secured to the side 22 of the housing.

50 In treating excrement, preferably human excrement to form a practical commercial fertilizer, the excrement in its natural state is placed in the pans 5 and heated by heat-

ed gases passing upwardly in a tortuous path through the casing, which will vaporize the liquid in the excrement, leaving a dry deposit in the pan which contains ammonium, phosphorous and potassium compounds in slightly varying quantities, which provides a valuable commercial fertilizer. 55

The elbows 17 and 24 and the joints 20 60 and 25 are positioned so that the heated gases will force the greater part of the vaporized by-products of the excrement into the pipes 15 and 16, and upwardly through these pipes and outwardly into the top of 65 the casing 1. Any parts of the by-products which may be condensed will pass into the pan 19 and be revaporized by the heated gases and pass out of the casing through the stack 4 with the gases for atmospherical distribution. 70

The heated gases passing over the pans 9 will have a tendency to deposit a limited amount of the carbon carried thereby upon the treated excrement which will add to the 75 fertilizing proclivities of the same.

What is claimed is:—

In an excrement drier, the combination, with a fire box, of a casing mounted upon said fire box, a plurality of pans removably 80 carried by said casing and disposed in staggered relation to each other, a top pan positioned centrally within the casing adjacent the top of the same, an outlet stack carried by the top of said casing, a pair of pipes 85 supported exteriorly of said casing, transversely extending pipes connected to said first named pipes and extending into said casing, said transversely extending pipes having their inner receiving ends positioned 90 above said pans, said exteriorly positioned pipes having their upper delivery ends extending into said casing above said top pan for delivering the vaporized liquid product of the excrement into the top of the casing 95 for revaporizing any condensed part thereof and for passage out of said stack.

In testimony whereof I affix my signature in presence of two witnesses.

WILLIAM F. PAGE.
